Claude F. Smider

ATTORNEY.

UNITED STATES PATENT OFFICE

FREDERIC E. DOUGLAS, OF HOPEDALE, MASSACHUSETTS, ASSIGNOR TO DRAPER CORPORATION, OF HOPEDALE, MASSACHUSETTS, A CORPORATION OF MAINE

SHUTTLE

Application filed February 9, 1932. Serial No. 591,850.

This invention relates to loom shuttles of the type adapted for automatic replenishment of the filling supply and has more particular reference to the means in such a shuttle for holding the filling carrier.

Shuttles of the aforementioned type are usually provided with a pair of opposed spring jaws for gripping the butt of the filling carrier, and a so-called cover which may include an inclined guide for positioning the incoming filling carrier longitudinally of the shuttle during the replenishing operation. Various arrangements of springs and inter-relations between the spring, cover member and shuttle body have heretofore been devised. However, such devices have been subject to the disadvantages that they loosen in the shuttle body under the impacts incident to repeated replenishing operations and that the springs frequently break after a comparatively short interval of use.

It is accordingly the principal object of my invention to provide a shuttle body, spring, and cover in which the parts are so constructed and inter-related as to materially lessen the possibility of the parts becoming loose or breaking.

Other objects will in part be hereinafter more specifically enumerated or will become apparent as the description proceeds.

Referring more particularly to the drawing:

Fig. 1 is a plan view of a portion of a shuttle embodying my invention;

Fig. 2 is a longitudinal sectional elevation of the shuttle shown in Fig. 1 and

Figs. 3 and 4 are perspective views of the shuttle spring and cover, respectively.

As shown in Figs. 1 and 2 the shuttle includes a body portion 1 provided with a cavity 2 for housing a filling carrier, or bobbin 3 of any suitable design. The butt end of the bobbin is provided with rings 4 adapted to be received in notches 5 in the opposed faces of spring jaws 6. These jaws are connected together, preferably by being integrally formed of one piece of metal, and the thus constituted bobbin supporting spring is located in an upwardly opening cavity 7 in one end of the shuttle body. The cavity 7 is of substan-

tially the same shape as the shank portion of the spring but is slightly larger than the latter, whereby the jaws of the spring are spaced from walls of the cavity from their inner bobbin gripping ends to a point A adjacent their outer ends. In other words, the spring, in so far as the walls of the cavity are concerned, is loosely positioned in the shuttle and the jaws are free to move relative to each other during the replenishing operation.

The shank portion of each jaw 6 is provided with an ear 9 extending laterally outward from the upper edge of the respective jaw. These jaws extend beyond the confines of the cavity 7 and are apertured as at 10 for the reception of fastening members.

The cover includes a rigid metallic plate 11 snugly received in the shuttle body and provided with triangularly related apertures 12, 13 and 14 the latter being positioned to come just above the outer end 15 of the space between the shank portions of the jaws and the others being positioned to coincide with the apertures 10 in the ears 9 when the plate occupies its normal position above the spring. In the present instance the cover also includes a downwardly inclined bobbin guide 16 and a spring supporting member 17 formed integrally with plate 11.

A second rigid metallic plate 18 is embedded in the shuttle body below the shank portion of the spring and is provided with three threaded apertures aligned respectively, with apertures 12, 13 and 14 in the plate 11.

When the spring and cover are assembled in the shuttle body with the plate 11 positioned over, and preferably though not necessarily in direct contact with, the shank portion of the spring, suitable fastening devices herein shown as screws 19 and 20 may be passed down through the apertures in the plate 11, ears 9, and the shuttle body and threaded into the lower plate 18, thereby securing the spring in the cavity in the shuttle body. A third screw 21 is then passed through the plate 11, between the shank portions of the jaws and through an aperture 22 in the member 17 and is threaded into the lower plate 18, thereby bracing the spring against lateral twisting.

It is readily apparent from the foregoing that the provision of fastening members passing through the rigid plate and the ears on the shuttle spring enables the parts to be 5 very firmly held in the shuttle body, while this fastening arrangement coupled with the fact that the spring is not transversely cramped by through bolts or the walls of the cavity permits free movement of the jaws 10 during the replenishing operation, thereby lessening spring breakage and precludes the possibility of the jaws bursting the shuttle when they are separated.

It is, of course, to be understood that the 15 specific embodiment of my invention herein disclosed is subject to variation without departing from the spirit of the invention as defined in the appended claims.

I claim:

1. A shuttle including a body having a bobbin supporting spring located in a cavity in one end thereof, said spring including opposed bobbin gripping jaws the shank portion of each of which is provided with a laterally 25 extending ear, a rigid plate covering said ears, and fastening devices passing through the plate, the ears and the shuttle body to thereby secure the spring in the said cavity.

2. A shuttle including a body having a bobbin supporting spring located in a cavity in one end thereof, said spring including opposed bobbin gripping jaws the shank portion of each of which is provided with a laterally 35 extending ear, rigid plates positioned respectively above and below said spring and snugly received in the shuttle body, and fastening devices passing through both plates, the ears and the shuttle body to thereby secure the spring in the said cavity.

3. A shuttle including a body having a bobbin supporting spring located in a cavity in one end thereof, said spring including opposed bobbin gripping jaws each of which is spaced from the walls of said cavity throughout substantially its entire length, the shank 45 portion of each jaw being provided with an ear extending laterally beyond the confines of the cavity, a rigid plate covering said ears and snugly received in the shuttle body and fastening devices passing through the plate, the ears and the shuttle body to thereby secure the spring in said cavity.

4. A shuttle including a body having a bobbin supporting spring located in a cavity in one end thereof, said spring including opposed bobbin gripping jaws each of which is spaced from the walls of said cavity from its inner bobbin gripping end to a point adjacent its outer end, the shank portion of each jaw 55 being provided with an ear extending laterally beyond the confines of the cavity, a rigid plate covering said ears, and fastening devices passing through said plate, the ears and the shuttle body to thereby secure the spring 60 in said cavity.

5. A shuttle including a bobbin having a bobbin supporting spring located in a cavity in one end thereof, said spring including opposed bobbin gripping jaws each of which is spaced from the walls of said cavity throughout substantially its entire length, the shank portion of each jaw being provided with an ear extending laterally beyond the confines in the cavity, rigid plates positioned respectively above and below said spring and snugly received in the shuttle body, and fastening devices passing through both plates, the ears and the shuttle body to thereby secure the spring in the said cavity.

6. A shuttle including a body having an upwardly opening cavity adjacent one end thereof, a spring loosely positioned in said cavity, said spring consisting of opposed jaws each provided with an ear extending laterally outwardly beyond the confines of the cavity, a bobbin guide having a plate formed integrally therewith which plate is snugly received in the shuttle body directly above said ears, another plate embedded in the shuttle body directly below the first named plate, and fastening devices passing through the plates, the ears and the shuttle body to thereby secure the spring in said cavity.
